LIGHTING FIXTURE

Edwin F. Guth, Webster Groves, Mo.

Application May 28, 1932. Serial No. 614,059

7 Claims. (Cl. 240—132)

My invention relates more particularly to that class of devices which are designed to hold an enclosing globe or shade for a lighting fixture.

Experience has shown that with the use of the present high powered gas filled lamps these globes are heated to such a degree that there is considerable expansion of the glass and if they are held rigidly by means of the small thumb screws formerly used for the purpose of holding shades in a canopy there is considerable breakage. On the other hand if loosely mounted the globe is liable to get out of alignment.

Numerous attempts have been made to produce screwless holders for this purpose but so far as I am aware these attempts have always been directed to a supporting device having a two or three point suspension with the result that the globe is not assured to be always in correct vertical alignment.

My invention has for its principal object to provide a screwless holder for globes or shades which will provide a four point suspension, thus ensuring its being supported correctly.

A further object being to provide a construction for the holder so that it can be conveniently and easily inserted in the globe and the globe can be conveniently removed for the purpose of cleaning or replacing lamp bulbs.

My means of accomplishing the foregoing objects may be more readily understood by having reference to the accompanying drawing which is hereunto annexed and made a part hereof, in which—

Fig. 1 is a side view of a socket equipped with my improved screwless holder, a fragmentary portion of the globe only being shown;

Fig. 2 is a top or plan view of the four point suspension member; and

Fig. 3 is a cross section taken on the line 3—3 in Fig. 2.

Similar reference numerals refer to similar parts throughout the entire description.

As shown in the drawing, an electric socket 1 is supported by a stud 2 in the usual manner. The external surface of this socket 1 is provided with threads which extend the entire length of the socket.

Mounted on these threads is my improved four point suspension member which consists of an upwardly extending cylindrical neck or stem 3 which has two flaring or outwardly extending arms 4 and 5 at its lower end. Threads 6 being rolled on the upper end of the neck or stem these threads fitting to the threads formed on the socket.

The corners 7 and 8, 9 and 10, of the arms 4 and 5 respectively, are bumped or stamped into V shaped points 11 and 12 thus giving a four point suspension upon which the glass globe 13 rests. This construction has a number of desirable points or features. First of all, forming as it does, a four point suspension tends to balance the globe in a vertical position at all times.

Secondly, the V shaped corrugations 11 and 12, the apex of which forms the suspension points, tend to stiffen the arms 4 and 5 thus permitting them to be made of lighter gauge metal and yet be sufficiently strong. Further, the operation of drawing in the corners of the arms slightly aids in the insertion of the holder into the globe.

Thirdly by providing the threaded portion of the neck or stem 3 and mounting it upon the external threads on the socket, I am able to obtain an adjustment of the globe so as to position the filament of the lamp bulb in the most desirable location.

A socket cover 14 is mounted upon the threads on the socket 1 serving to cover the socket 1 from view but primarily acting as a lock nut to lock the neck or stem 3 in place when it has been adjusted to position the lamp filament (not shown) correctly.

An annular member 15 provided with a downwardly depending flange 16 is provided to be placed over the neck or stem 3, the flange 16 extending down sufficiently to cover the neck 17 of the globe 13, only a fragmentary portion of which is shown, this annular member 15, when in position, giving a desirable finish to the holder. At the same time it will be apparent that there are no thumb screws or bushings employed and there is no compression on the globe so that there is no danger of breakage due to it being rigidly supported.

Having described my invention what I regard as new and desire to secure by Letters Patent is:

1. In a lighting fixture, the combination with a socket having external threads extending throughout its length, of a globe support comprising a stem having threads thereon which fit the external threads on said socket, a pair of outwardly extending arms on said stem, each of which has a pair of suspension points formed thereon adapted to contact with a globe, an annular enclosing cap mounted on said stem, said cap having a downwardly depending flange to enclose the neck of a globe, and means to lock said stem on said socket.
2. In a lighting fixture, the combination with

a socket having external threads extending throughout its length, of a globe support comprising a stem having threads thereon which fit the external threads on said socket, a pair of outwardly extending arms on said stem, a pair of inverted V shaped corrugations on each arm, the apex of said V shapes forming four points which engage a globe, an annular enclosing cap mounted on said stem, said cap having a downwardly depending flange to enclose the neck of a globe, and means to lock said stem on said socket.

3. In a lighting fixture, the combination with a socket having external threads extending throughout its length, of a globe support comprising a stem having threads thereon which fit the external threads on said socket, a pair of outwardly extending arms on said stem, each of which has a pair of suspension points formed thereon adapted to contact with a globe, an annular enclosing cap mounted on said stem, said cap having a downwardly depending flange to enclose the neck of a globe, means to lock said stem on said socket, said means forming a socket cover.

4. In a lighting fixture, the combination with a socket having external threads extending throughout its length, of a globe support comprising a stem having threads thereon which fit the external threads on said socket, a pair of outwardly extending arms on said stem, each of which has a pair of suspension points formed thereon adapted to contact with a globe, an annular enclosing cap mounted on said stem, said cap having a downwardly depending flange to enclose the neck of a globe, means to lock said

stem on said socket, said means forming a socket cover having threads thereon which fit the external threads on said socket.

5. In a lighting fixture, the combination with a socket having external threads extending throughout its length, of a globe support comprising a stem having threads thereon which fit the external threads on said socket, a pair of outwardly extending arms on said stem, each of which has a pair of suspension points formed thereon adapted to contact with a globe, an annular enclosing cap mounted on said stem, said cap having a downwardly depending flange to enclose the neck of a globe.

6. In a lighting fixture, the combination with a socket having external threads extending throughout its length, of a globe support comprising a stem having threads thereon which fit the external threads on said socket, a pair of outwardly extending arms on said stem, a pair of inverted V shaped corrugations on each arm, the apex of said V shapes forming four points which engage a globe, an annular enclosing cap mounted on said stem, said cap having a downwardly depending flange to enclose the neck of a globe.

7. A globe support stamped from sheet metal comprising a cylindrical portion adapted to surround an electric socket, a pair of outwardly extending arms on said cylindrical portion, each of said arms having a pair of inverted V shaped corrugations thereon, the apex of said V shapes forming four points adapted to engage the inside of a globe adjacent its neck.
